(57) **CLAIM**

The ornamental design for an interchangeable cover for a mobile phone, as shown and described.

DESCRIPTION

FIG. 1 is an isometric perspective view of the interchangeable cover design of the invention;

FIG. 2 is a first side view directed towards the open side of the interchangeable cover;

FIG. 3 is a second side view directed towards the side of the interchangeable cover with the side surface;

FIG. 4 is a front view of the front side of the interchangeable cover;

FIG. 5 is a back view of the backside of the interchangeable cover;

FIG. 6 is another perspective view, looking towards the open top and the side of the interchangeable cover with the side surface; and,

FIG. 7 is yet another perspective view, looking towards the open bottom and the open side of the interchangeable cover.
